VACUUM TUBE SOCKET

Scipione M. Del Camp, Maywood, Ill., assignor to
Cinch Manufacturing Corporation, Chicago,
Ill., a corporation of Illinois

Application December 17, 1938, Serial No. 246,408

5 Claims. (Cl. 173—328)

This invention relates to sockets and more especially to sockets for use in combination with radio vacuum tubes.

One object of my invention is the provision of a socket having a shielding means adapted for use with a vacuum tube in which the leads, including the control grid terminal, end at the base of the tube. The shielding means is disposed in a way to provide a wall interposed between the leads and connected to a ground such as the radio chassis. The construction of my improved device is particularly useful for shielding the lead connection of the grid from the lead connection of the plate.

Another object of my invention is to provide a contact spring, the purpose of which is to receive a lead pin in electrical connection with the metal envelope of a so-called "all-metal tube" for grounding the metal envelope.

Another object of my invention is the provision of conducting means carried by the socket electrically connecting the shielding means with the contact spring for receiving the metal envelope grounding pin so as to bring all ground connections together at a common point.

A further object relates to means electrically connecting the shielding devices with a chassis of a radio set so as to ground the devices.

Other objects and uses of my invention will be apparent from inspection of the drawings and specification hereinbelow set forth.

Referring to the drawings, in which I have illustrated preferred forms of my invention:

Fig. 1 is a top plan view of my first form of improved socket member;

Fig. 2 is a bottom plan view of the socket member shown in Fig. 1;

Fig. 3 is a side view of my first form of socket member;

Fig. 4 is a top view of my first form of socket member before attachment of the upper insulating plate so as to show the relative position of parts of my improved device;

Fig. 5 is a sectional view along the line 5—5 of Fig. 1 and showing the socket member secured to a supporting panel;

Fig. 6 is a top view of a second form of my invention;

Fig. 7 is a bottom view of the socket shown in Fig. 6;

Fig. 8 is a side plan view of the socket member shown in Figs. 6 and 7;

Fig. 9 is a top plan view of my second form of socket member with the upper plate removed; and

Fig. 10 is a sectional view along the line 10—10 of Fig. 6 and showing the socket member secured to a supporting panel.

Referring to the first form of my invention as illustrated in Figs. 1-5 of the drawings, I have shown a socket which includes an insulating base comprising an upper plate 1 and a lower plate 2 formed of suitable insulating material. Contact springs 3 are carried by the insulating base for receiving contact pins of a cooperating vacuum tube (not shown) and the plates 1 and 2, together with the contacts 3, are held together by a metal retainer member 4. The retainer member 4 has a dished body portion 5 having flanges 6-6 at opposed ends which are apertured to receive rivets 7 whereby the retainer member may be secured in direct electrical connection to a metal panel 8 (Fig. 5), which may be the chassis of a radio set, without resorting to soldering.

10 The body portion 5 of the retainer member has lug portions 9 in clamped engagement with the top surface of the insulating plate 2 for holding the parts of the socket member in assembly.

The upper plate 1 has, in my preferred form, 15 a central non-circular aperture 10 in alignment with a similarly-shaped aperture 11 of the plate 2. In conjunction with the apertures 10 and 11 I have provided a central metal member 12, which may be similar to that illustrated and described in connection with my Patent No. 2,230,028, patented January 28, 1941, filed August 20, 1935. The metal member 12 is of non-circular cross-section to correspond with the non-circular shape of the apertures 10 and 11. The 20 metal member 12 comprises a rivet portion 12^a having an extension at one end in the form of an apron 13 extending below the bottom plate, as illustrated in Figs. 3 and 5. The apron 13 has a shoulder portion 14 adjacent its junction with the rivet 12^a in engagement with the lower surface of the plate 2, and the end of the rivet 12^a opposed to the apron 13 is turned outwardly to form a flange 15 engaging the upper surface of the plate 1, as most clearly shown in Fig. 5. 25 Thus, by reason of engagement of the shoulder 14 and flange 15 with the respective plates 2 and 1, the metal member is securely fixed to the socket base. In the absence of the retainer member 4, the metal member 12 may provide 30 the only means holding the plates 1 and 2 together before attachment of the socket to a support. One purpose of the metal member 12 is to provide a guide for receiving a central guide pin of a vacuum tube (not shown) having a shape 35 conforming to the cross-sectional shape of the

hollow member thereby to locate lead pins (not shown) of the tube with proper contacts 3. The apron 13 also serves as a shielding means between certain contacts 3, as will be hereinafter described. It should be understood, however, that I do not wish to be limited by a metal member having the apron 13, as shown in the drawings, as the rivet portion 12^a, in the absence of the apron, would act as a suitable shielding means in many cases.

The bottom plate 2 has a series of contact-receiving apertures 16 arranged in a circle around the central aperture 11, and the top plate 1 has a series of pin-receiving apertures 17 arranged in a circle and in alignment with the contact-receiving apertures 16. Each of the contact springs 3, in the preferred form of my invention, is preferably formed to have a substantially tubular contact-receiving portion 18 projecting through an aperture 16 of the bottom plate to a position beyond the lower side of the bottom plate. The pin-receiving portions 18 have laterally-extending means such as the supporting ears 19 (Fig. 4) disposed between the plates 1 and 2 and limiting axial movement of the pin-receiving portion 18 through the aperture 16.

As a means for grounding to the chassis the metal member 12 and one of the contact springs, hereinafter designated by the letter "A", which has for its function to receive a tube pin which is in electrical connection with the metal envelope of a metal tube, I have provided a conducting strip 20. The conducting strip 20, as most clearly shown in Figs. 4 and 5, comprises a relatively flat portion 21 disposed in adjacent relation to the upper surface of the insulating plate 2 and having an aperture 22 in alignment with an aperture 16 of the plate 2. A lug 23 is provided at one end of the plate 21 which extends from the plate in integral angular relation thereto. The lug 23 projects into the opening 11 of the base 2 and is in engagement with the metal member 12 when the metal member is in final fixed relation with the socket, thus establishing electrical connection between the metal member and the conducting strip. An opposite end of the portion 21 from that having the lug 23 is provided with an integral hook-shaped portion 24 clamped over the outer peripheral edge of the plate 2 and in electrical engagement with the dish-shaped portion 5 of the metal retainer when the parts of the socket are in assembled relation, as most clearly shown in Fig. 5. As a result of this construction, the metal member 12 is grounded through the conducting strip 20 and the metal retainer member 4 to the panel 8 of the radio chassis. In order that certain leads of the vacuum tube may be grounded to a common point, the contact spring A is preferably assembled with the socket member so as to be electrically engaged with the conducting strip 20. This is accomplished through projecting the pin-receiving portion 18 of the contact A through the aperture 22 of the conducting strip and the corresponding aligned aperture 16 of the plate 2 with the result that the supporting ears 19 of the socket contact A electrically engage the outer surface of the portion 21 of the conducting strip adjacent the aperture 22 (Figs. 4 and 5). The contact spring A is maintained in the aforesaid electrical engagement with the conducting strip by reason of the top insulating plate 1, which, in the completed socket, is clamped tightly down against the supporting ears, as most clearly shown in Fig. 5.

Thus it will be seen that the metal member 12,

due to its physical construction, acts a shield by reason of the fact that it stands as an obstruction between certain of the contact springs and as a result maintains a very low grid-to-plate capacitance even though the leads are relatively close together. The conducting strip 20 is constructed in a way to effect the shortest possible path for grounding the shield to the radio chassis. Furthermore, the electrical connection between the contact spring A and the conducting strip 20 provides a simple and inexpensive method for grounding the envelope of a metal tube to the chassis.

Referring to the second form of my invention illustrated in Figs. 6-10, I have shown a shielded socket which differs from my first form of socket, particularly by the fact that it has no metal retainer member for carrying out the purposes of the retainer member 4 of my first form of socket. My second form of socket includes an insulating base secured directly to a metal supporting panel and a conducting means carried by the base adapted to be soldered directly to the metal supporting panel for grounding the shielded connections.

My second form of socket includes a base comprising upper and lower plates 25 and 26 formed of suitable insulating material. Contact springs 27 are carried by the base for receiving suitable pin leads (not shown) of the vacuum tube. A contact spring, hereinafter designated as "B", for receiving a tube pin in electrical connection with the metal envelope of the tube for grounding the same, is carried by the socket and differs in construction from the contact springs 27, as will be described. The insulating plates 25 and 26 have registering apertures 28 at opposite ends for receiving rivets 28^a (Fig. 10) or other suitable attaching means whereby the socket base may be secured to a metal supporting panel 29. The upper plate has a central non-circular aperture 30 in registering relation with a similarly-shaped aperture 30^a of the lower plate 26 (Fig. 10). A metal member or shielding means, adapted, in my preferred construction, to provide an obstructing wall between certain of the contacts 27 in the manner of the shielding means 12 of the first form of my invention, is secured to the socket base within the apertures 30 and 30^a. The shielding means is in the form of a rivet-like ferrule 31 having a cross-sectional shape conforming with that of the apertures 30 and 30^a whereby it also serves as a locating guide and is adapted to receive a guide prong of a vacuum tube which is of corresponding cross-sectional shape. The ferrule 31 is passed through the apertures 30 and 30^a and is headed over at its opposite ends to clamp the plates 25 and 26 rigidly together. It should be understood, however, that I do not wish to be limited to the specific form of ferrule 31 which I have illustrated in connection with my second form of shielded socket because a shielding means of different shape, such, for example, as the aproned ferrule illustrated in connection with my first form of socket, would effect a similar result. The lower plate 26 has a circular series of apertures 32 for receiving pin-receiving portions of the contact springs 27, and the upper plate 25 has a series of pin-receiving apertures 33 in registry with the apertures 32 of the plate 26.

Each of the contacts 27 has a substantially tubular pin-receiving portion 34 extended through an aperture 32 of the plate 26 and supporting means integral with the portion 34 in the form of ears 35 disposed in adjacent relation to the upper

surface of the plate 26. A terminal lug 36 extends from the portion 34 through an opening 32^a of the plate 26. As a means for grounding the ferrule 31, I have provided, in my second form of socket device, a conducting strip 37 comprising a flat portion 38 in adjacent relation to an upper surface of the plate 26 and having an aperture 39 in alignment with an aperture 32 of the plate 26 (Fig. 10). An integral hook-shaped portion 40 at one end of the flat portion 38 is extended into the aperture 30^a of the plate 26 and clamped over the lower surface of the plate. Thus the hook-shaped portion 40 is engaged with the ferrule 31 when the parts of the socket are in final assembly so as to connect electrically the ferrule with the conducting strip. The opposite end of the conducting strip 37 from that having the hook-shaped portion 40 preferably terminates at the innermost edge of the aperture 32^b correlative to the specific aperture 32 with which the aperture 39 of the conducting strip is in alignment.

The contact spring B is preferably of one-piece construction and serves not only to make electrical connection with a grounding pin (not shown) of the metal envelope of the tube for grounding the envelope, but, also, to connect electrically the conducting strip with the panel 29 so as to ground the shielding means 31. The contact spring B, in my preferred form, has a substantially tubular pin-receiving portion 41 at one end extended through the aperture 39 of the conducting strip and the aligned aperture 32 of the plate 26. Supporting ears 42 (Figs. 9 and 10) project from one end of the pin-receiving portion 41 and are disposed between the insulating plates 25 and 26 in superposed adjacent relation to the upper surface of the flat portion 38 of the conducting strip. A tail 43, integrally joined to the end of the pin-receiving portion 41, is disposed between the plates 25 and 26 and extends beyond the peripheral edges of the plates. The tail 43 has a portion 44 adjacent the pin-receiving portion 41 in superposed adjacent relation to the flat portion 38 of the conducting strip. Thus the ears 42 and the portion 44 of the contact B engage the conducting strip to establish electrical connection between the contact B and the strip. A pair of lugs 45 (Fig. 7) may be struck from the tail adjacent an end of the portion 44 and extended into the aperture 32^b (Fig. 10) so as to aid in maintaining the contact spring B in fixed position. An opposite end of the tail 43 from that joined to the pin-receiving portion 41 has a soldering portion 46 projected slightly above the normal plane of the tail 43 and adapted to be soldered to the under surface of the metal panel 29, as at C (Fig. 10). The upper insulating plate 25, which is clamped rigidly to the lower plate 26 by means of the metal ferrule 31, serves to maintain the contact spring B in electrical engagement with the conducting strip 37.

Thus it will be seen by my second form of invention that the ferrule 31, which acts as a shielding means between certain contact springs in the manner of the member 12 of the first form of my invention, is grounded to the chassis of the radio set through the conducting strip and the contact spring B. At the same time the contact spring serves to ground the metal envelope of the tube to the chassis. Also, as a result of my invention, all the grounding connections of the socket are brought to a common point so as to effect a simple and inexpensive shielded device. Furthermore, I have provided a grounding con-

nection having the shortest possible path from leads to ground.

It will be understood that modifications and alterations of the shielded sockets hereinabove described may be made without departing from the scope and spirit of my invention. Therefore, although I have illustrated and described preferred forms of my invention, I do not wish to be limited thereby because the scope thereof is best set forth in the following claims.

I claim:

1. A socket comprising, in combination, a pair of superposed insulating plates having a metal central hollow member, a plurality of socket contact members assembled with said plates in a series around said central hollow member, a conducting strip disposed between said insulating plates in electrical engagement with said hollow member and one of said socket contacts, and means maintaining said conducting strip in said electrical engagement with said parts.

2. A socket comprising, in combination, a pair of superposed insulating plates secured within a cup-shaped metal retainer member, said plates having a metal central hollow member, a plurality of socket contact members assembled with said plates in a series around said central hollow member, a conducting strip maintained in assembly with said socket between said insulating plates, said conducting strip being in electrical engagement with said hollow member, one of said socket contacts and said retainer member, and means maintaining said conducting strip in said electrical engagement with said parts.

3. A socket comprising, in combination, upper and lower insulating plates secured to a metal retainer, said plates having a registering series of contact apertures and registering guide apertures, contact members carried by said plates, each of said contact members having a prong-receiving portion extending into an aperture of said lower plate and a mounting portion overlying said lower plate adjacent said respective aperture for supporting said contact, a flat conducting strip disposed between said upper and lower plates, said strip having a portion at one end disposed within at least one of said guide apertures, a portion at the other end in electrical engagement with said retainer member and a portion intermediate said ends having an opening in alignment with a contact aperture of said lower plate and receiving the prong-receiving portion of one of said contact members, the mounting means of said last-mentioned contact being disposed in superposed adjacent relation to said conducting strip whereby said contact and said conducting strip are electrically connected together, and a metal member secured in said guide apertures in electrical engagement with said portion of said conducting strip extended into said guide aperture.

4. A socket installation comprising, in combination, a socket comprising upper and lower superposed insulating plates having a registering series of contact apertures and registering guide apertures, a metal hollow member secured within said guide apertures, socket contacts carried by said plates having prong-receiving portions extended into said contact apertures of said lower plate, a flat conducting strip disposed between said insulating plates having an aperture in alignment with one of said contact apertures and a portion in electrical engagement with said hollow member, said conducting strip receiving the prong-receiving portion of one of said socket con-

tacts through its aperture, means electrically connecting said conducting strip and said last-mentioned socket contact, and said last-mentioned socket contact having means whereby it may be electrically connected with another part.

5. A socket installation comprising, in combination, a metal supporting panel, a socket member secured to said panel, said socket comprising upper and lower superposed insulating plates having a registering series of contact apertures and registering guide apertures, a metal hollow member secured in said guide apertures, a conducting strip disposed between said insulating plates having an opening in alignment with one of said contact apertures and a portion in elec-

trical engagement with said hollow member, contact members carried by said plates, each of which has a prong-receiving portion extending into an aperture of said lower plate, said conducting strip receiving the prong-receiving portion of one of said contacts through its opening, said last-mentioned contact having means in electrical engagement with said conducting strip and a tail portion extending beyond the outer edges of said socket, said tail having a portion in fixed electrical engagement with said supporting panel whereby said last-mentioned contact and said hollow member are grounded to said panel.
